UNITED STATES PATENT OFFICE.

GEORGE E. CRAMER, OF TARPON SPRINGS, FLORIDA, ASSIGNOR OF ONE-THIRD TO
FRANK M. CARTER, OF PICNIC, FLORIDA, AND ONE-THIRD TO JOHN E. LARSEN, OF
ST. PETERSBURG, FLORIDA.

FOOT-POWER HAMMER.

1,099,025.

Specification of Letters Patent.

Patented June 2, 1914.

Application filed November 17, 1913. Serial No. 801,481.

To all whom it may concern:

Be it known that I, GEORGE E. CRAMER, a citizen of the United States, residing at Tarpon Springs, in the county of Hillsboro 5 and State of Florida, have invented certain new and useful Improvements in Foot-Power Hammers; and I do hereby declare the following to be a full, clear, and exact description of the invention, such as will 10 enable others skilled in the art to which it appertains to make and use the same.

The present invention relates to power hammers, and has for its purpose to provide a construction of hammer which will be 15 capable of delivering heavy and cushioned blows in rapid succession; and wherein the retracting movements of the hammer are cushioned and utilized to impart the initial forces of the next succeeding blows.

20 A further purpose of the invention is to provide a structure which is especially adapted for use in blacksmiths' shops, foundries, and railroad shops; and which is of simple construction, and manner of operation, and inexpensive to install.

In the accompanying drawings forming a 25 part of this application, and in which similar reference symbols indicate corresponding parts in the several views:—Figure 1 is a perspective view of the power hammer complete; Fig. 2 is a transverse sectional view of a detail taken on the line 2—2 of Fig. 1, and looking in the direction of the arrow; and Fig. 3 is a top plan sectional view, showing the manner of connection between the actuating links and the hammer supporting shaft.

Referring to the construction in detail, the machine comprises a base 1 having 30 mounted thereon a supporting frame, consisting of four upright beams 2, connected in pairs or sections by cross bars 3, 4 and 5, and said sections are connected by the cross beams 6 and 7; the whole forming a rigid structure.

The shaft 8 is journaled at the upper end of the frame in the cross bars 5, and has its respective ends provided with crank arms 9 and 10 being connected, respectively, with 35 the pair of link rods 11 through which said cranks are actuated. A lever 12 is secured to the shaft 8 to oscillate therewith, and has mounted thereon the helve bar 13 of the hammer. Said bar is provided with

an aperture, through which the lever 12 passes, and a pin 14 on said lever holds the helve bar in position.

The hammer has a substantial and resili- 55 ent connection with the lever 12, through the medium of the leaf spring 15 compris- 60 ing two strips that are secured to the free end of the lever 12 by a clamping plate 16 and a nut 17. The free ends of the spring 15 engage with the helve bar 13 on opposite sides of the projecting lever por- 65 tion; the spring ends 18 being bent under and disposed against the helve bar, and the spring ends 19 are connected by a pin 20 adapted to have movement within the slot provided by the retaining plate 21. By 70 having this resilient connection between the operating lever and the hammer, the inertia of the latter may be more readily overcome, thus making the machine easy of operation, and there is the further advantage that the 75 delivery blow is of longer duration than would be the case if the connection in question were a rigid one.

A pair of treadle bars 22 are fulcrumed on a shaft 23 secured to the supporting 80 frame, and a treadle 24 connects said treadle bars at the free ends thereof, and enough in advance of the anvil to give perfect freedom to the operator.

The link rods 11 connect the treadle at 85 the points 26 with the cranks 9 and 10 of the shaft supporting the hammer, and by actuating the treadle 24 the hammer will be operated by the operator, as will be clearly understood.

The retraction spring 27 is anchored at one end to the bar 23, and at its opposite end is connected by a link 28, carried by lugs 29 (see Fig. 3), projecting from the shaft 8.

The retracting movements of the lever are adapted to be cushioned by means of a bar 30, that is movably mounted in a pair of guide members 31 secured to the anvil block 32, and said bar 30 has its respective ends 100 constructed with hooks 32^a, that engage the free ends 33 of a pair of springs 34, which are anchored to the base 1 of the supporting structure. With this arrangement, the treadle bars 22 will, on their retracting 105 movements be brought forcibly into engagement with the resiliently-mounted bar 30, and as a consequence the upward swing of

the hammer will be cushioned and stopped, and the counter-recoil movement of the springs 34 acting through the bars 30 and 22 will forcibly return the hammer, or impart 5 thereto its initial stroke.

It is obvious that various changes might be made in the herein-described construction without departing from the spirit of my invention.

10 I claim:—

1. In a power hammer, the combination of a supporting structure; a crank shaft journaled on said structure; a lever fixedly mounted on said crank shaft; a hammer 15 helve fitted on said lever; a spring secured to said lever and having resilient engagement with said hammer helve; a treadle-bar fulcrumed on the supporting structure; a treadle on said treadle-bar; a link connection 20 between said treadle and the crank shaft for actuating the hammer; and a retraction means for the hammer, substantially as described.

2. In a power hammer, the combination 25 of a supporting structure; a crank shaft journaled on said structure; a lever fixedly mounted on said crank shaft; a hammer helve fitted on said lever; a leaf spring secured to said lever and having its respective 30 ends in resilient engagement with said hammer helve; an anvil supporting block; a

pair of treadle-bars disposed to either side of said anvil supporting block and fulcrumed on said supporting structure; a treadle mounted on said treadle-bars; a pair 35 of links connecting said treadle with said crank shaft for actuating the hammer; and a retraction spring anchored to said supporting structure and connected to said crank shaft; substantially as described. 40

3. In a power hammer, the combination of an upright supporting frame; a shaft journaled on said frame and having cranked ends; a lever fixedly mounted on said shaft; a hammer helve fitted on said lever; a leaf 45 spring secured to said lever and having its respective ends in frictional and resilient engagement with said hammer helve; a pair of treadle-bars disposed to either side of and fulcrumed on said frame; a treadle connecting 50 said treadle-bars; a pair of links connecting said treadle with the crank ends of said shaft for actuating the hammer; and a retraction spring for the hammer, substantially as described. 55

In testimony whereof, I affix my signature, in presence of two witnesses.

GEORGE E. CRAMER.
